UNITED STATES PATENT OFFICE.

PETER M. KLING, OF ALLEGHENY, PENNSYLVANIA.

CAR-TRUCK.

No. 839,601.

Specification of Letters Patent.

Patented Dec. 25, 1906.

Application filed March 20, 1906. Serial No. 307,025.

To all whom it may concern:

Be it known that I, PETER M. KLING, a citizen of the United States, and a resident of Allegheny, in the county of Allegheny and State of Pennsylvania, have invented a new and useful Improvement in Car-Trucks, of which the following is a specification.

My invention relates to six-wheel trucks for cars.

10 It is applicable to railway-cars and has special features of utility in its application to six-wheel trucks designed for motor-cars.

The primary purpose of my invention is to devise a construction of truck and arrangement of springs therefor which will obviate the practical difficulties experienced in providing springs of adequate strength and affording room for the motors without unduly extending the length or other dimensions of 20 the truck. To this end I have devised an improved center frame and bolster construction and elliptic spring-support, consisting in part of four double elliptic springs diagonally arranged, so as to provide room for the 25 motor and also provide for the lateral and longitudinal swinging motion existing in six-wheel trucks of most approved construction. I am thus enabled to retain all the good 30 qualities of the six-wheel truck while accommodating two of the largest motors made for electric cars.

The improvements particularly consist in a novel construction of spring-carrying frame, a novel construction of bolster-frame, and a 35 novel combination of diagonally-arranged double elliptic springs interposed between the carrying-frame and the bolster-frame, through the medium of which the latter is supported.

40 In order that my invention may be fully understood, I will proceed to describe a practical embodiment thereof with reference to the accompanying drawings, in which—

Figure 1 is a plan view of a six-wheel 45 truck, illustrating my invention. Fig. 2 is a side view thereof. Fig. 3 is a plan view of the central portion of said truck on a larger scale. Fig. 4 is an end elevation of said central portion of the truck, showing in section 50 the longitudinal I-beams which extend from end to end of the truck resting through coil-springs and equalizer on the axle-bearings, as best shown in Fig. 2. Fig. 5 shows in elevation the central transverse bolster and in 55 transverse section the longitudinal truss-beams on which its ends are supported. Fig.

6 is a side elevation of the central part of the truck with the longitudinal I-beams, equalizers, and journal-box removed and the projecting axle-journal shown in section. Fig. 60 7 is a detail side view of one of the longitudinal truss-beams which support the end of the central bolster. Fig. 8 is a detail plan of one side of a supporting-frame on which the elliptic springs are seated. 65

The central bolster is made up of two plates 1^a, bent as shown in Figs. 4 and 5, to impart transverse strength and rigidity and united at their ends, where they rest on longitudinal truss-beams 2. (Shown in plan in Fig. 70 3, in transverse section in Fig. 5, and in side elevation in Figs. 6 and 7.) The lower members 1^a of the bolster are turned up at their ends, as shown at 1^b, Figs. 4 and 5, to afford thrust-bearings for the ends of the upper 75 member 1 and give greater rigidity thereto. On the elevated center of the upper member 1 is the bolster plate or boss 1^c, on which the car-body rests in customary manner with capacity for limited oscillatory motion in a horizontal plane. 80

The rocking motion of the car-body in a transverse vertical plane is sustained by arc-formed bosses 3 on arched side plates 4, bolted at their ends to transverse plates 5, 85 which rest on brackets 6, by which they are secured to the longitudinal truss-beams 2. The truss-beams 2 rest at their ends on elliptic springs 7, four in number, diagonally arranged, as indicated in the plan views, Figs. 90 1 and 3. The elliptic springs 7 are secured at top by clips 7^a, by which the leaves of the upper member of the spring are united, and are seated at bottom on plates 8, having oblong apertures 9, Fig. 8, for reception of the clips 95 10, which surround and unite the plates forming the lower member of the respective elliptic springs. The apertured seat-plates 9 are bolted on the corners of a quadrangular supporting-frame, one side of which is shown 100 in the detail plan view, Fig. 8, consisting of transverse plates or bars 11 and longitudinal connecting plates or bars 11^a and longitudinal rods or bars 12 directly underneath the spring-seats 8, with projecting ends forming 105 round gudgeons 12^a, which are received by eyes on the lower end of swinging hangers 13, as shown in Fig. 4, depending by eyes in their upper ends from bolts 14 in saddle-plates 15, fixed by bolts 16 to the top of brackets 17, 110 which are in turn bolted to strong transverse beams 18, resting and secured at their ends in

brackets 19, which are firmly bolted to I-beams 20, extending from end to end of the truck, forming the side beams of the truck-frame and united at their ends by corner-pieces 21 to the transverse beams 22 of the frame. The longitudinal bars 11^a and 12 are bent downward, as indicated in dotted lines in Fig. 6, to pass under the axle and afford ample vertical play for the spring movement. The side beams 20 rest through the medium of strong spiral springs 23 on equalizers 24, by which the weight is properly distributed to the center journal-bearing 25 and the two end journal-bearings 25^a on each side of a six-wheel truck in customary manner, the pedestals 26 in which the bearings play being fixed to the side beams 20, as shown in Fig. 2.

The central wheels are indicated at W and the end wheels at W', mounted, respectively, on the axles A and A' in customary manner.

My invention as above described possesses great utility in providing spring-support of ample capacity within smallest possible limits and by diagonal arrangement of the springs providing room for motors of large size and by the manner of hanging the spring-supports providing for the free oscillation of the body both laterally and longitudinally with relation to the truck-wheels.

Having thus described my invention, the following is what I claim as new therein and desire to secure by Letters Patent:

35 1. In a six-wheel truck for cars the combination of a central bolster and bolster-frame and diagonally-arranged elliptic springs on which they are supported.

2. In a car-truck the combination of a central bolster and bolster-frame, diagonally-arranged elliptic springs on which said frame is supported, a spring-supporting frame and swinging hangers by which said spring-supporting frame is suspended from the carrying-frame of the truck.

45 3. In a car-truck the combination of a central transverse bolster, longitudinal truss-beams supporting the ends of said bolster, diagonally-arranged elliptic springs supporting the ends of said longitudinal truss-beams and suitable supports and hangers sustaining the elliptic springs from the carrying-frame of the truck.

4. In a car-truck the combination of a central transverse bolster having a central bear-

ing for the car-body longitudinal truss-beams on which the ends of said transverse bolster are supported, a bolster-frame, having side plates provided with bearings to sustain the lateral oscillations of the body and suitable supporting connections between said side bearing-plates and the longitudinal truss-beams.

5. In a car-truck, the combination of a transverse bolster for supporting the car-body, a quadrangular bolster-frame including side plates to sustain lateral oscillations of the body, elliptic springs on which said bolster and bolster-frame are supported, a quadrangular supporting-frame for said springs and means sustaining said spring-supporting frame from the carrying-frame of the truck.

6. In a car-truck, the combination of a transverse bolster for supporting the car-body, a quadrangular bolster-frame including side plates to sustain lateral oscillations of the body, diagonally - arranged elliptic springs on which said bolster and bolster-frame are supported, a quadrangular supporting-frame for said springs and means sustaining said spring-supporting frame from the carrying-frame of the truck.

7. In a six-wheel car-truck, the combination of a transverse bolster adapted to support the car-body and permit relative oscillation thereof on a vertical axis central to the bolster, a quadrangular bolster-frame having side plates carrying arc-formed bearings concentric with the vertical axis of oscillation, 90 to arrest and sustain oscillation of the body in a transverse vertical plane, springs on which said bolster and bolster-frame are supported, a quadrangular supporting-frame for said springs and means sustaining said spring-supporting frame from the carrying-frame of the truck.

8. The combination of a transverse bolster adapted to support the car-body with means to permit relative oscillatory motion on a vertical axis, arched side plates, transverse plates and longitudinal beams supporting said side plates and arc-formed bearings on said side plates, to sustain and check the lateral oscillation of the car-body, substantially 105 as described.

PETER M. KLING.
